US0D1042874S

(12) **United States Design Patent** (10) **Patent No.:** **US D1,042,874 S**
(45) **Date of Patent:** **** Sep. 17, 2024**

(54) **SAMPLE COLLECTION DEVICE**

(71) Applicant: **Cue Health Inc.**, San Diego, CA (US)

(72) Inventors: **Hiruni H. Perera**, San Diego, CA (US); **Clint Sever**, San Diego, CA (US); **Joseph D. Kowalski**, San Diego, CA (US); **Michael Yep**, San Diego, CA (US); **Eric E. Johnson**, San Diego, CA (US)

(73) Assignee: **CUE HEALTH INC.**, San Diego, CA (US)

(**) Term: **15 Years**

(21) Appl. No.: **29/847,454**

(22) Filed: **Jul. 25, 2022**

(51) LOC (14) Cl. **24-02**

(52) U.S. Cl.

USPC **D24/133**

(58) **Field of Classification Search**

USPC D24/133, 107, 119, 141, 146, 147, 186,
D24/216, 223, 231

CPC B01L 3/5029; A61B 10/02; A61B
2010/0216; A61B 2010/0074

(57) **CLAIM**

We claim the ornamental design for a sample collection device, as shown and described.

DESCRIPTION

FIG. 1 is a top, rear, left side perspective view of a sample collection device according to an example embodiment; FIG. 2 is a bottom, rear, right side perspective view thereof; FIG. 3 is a top, front, left side perspective view thereof; FIG. 4 is a top plan view thereof; FIG. 5 is a bottom plan view thereof; FIG. 6 is a right side elevation view thereof; FIG. 7 is a left side elevation view thereof; FIG. 8 is an enlarged front elevation view thereof; and, FIG. 9 is an enlarged rear elevation view thereof. The broken lines in the drawings are for the sake of illustrating portions of the sample collection device that form no part of the claimed design.

1 Claim, 6 Drawing Sheets
